UNITED STATES PATENT OFFICE.

MOSES G. FARMER, OF NEW YORK, N. Y.

TELEGRAPH SYSTEM.

SPECIFICATION forming part of Letters Patent No. 349,214, dated September 14, 1886.

Application filed June 11, 1886. Serial No. 204,835. (No model.)

To all whom it may concern:

Be it known that I, MOSES G. FARMER, a citizen of the United States, and a resident of New York, in the county and State of New

5 York, have invented certain new and useful Improvements in Telegraph Systems, of which the following is a specification, reference being had to the drawing accompanying and forming a part of the same.

10 My invention is embodied in a system or combination of instruments and electric circuits for sending and receiving telegraphic signals by means of induced or secondary currents.

The improvements which constitute my invention are a novel arrangement of circuits, whereby a great saving of battery-power is effected, and the combination therewith of a circuit-closer and a circuit-reverser, by means of which the working of a line is greatly facilitated.

15 One of the methods of operating a telegraphic line heretofore practiced has been to use an induction-coil at each terminal, the primary coil of each induction-coil being included in a local circuit with a battery and the secondary coil in the main line. To produce the signaling-currents, the direction of the current in one of the primaries was reversed by means of a key, and a corresponding current-impulse

20 thereby induced in the secondary coil and main line. The manipulation of a circuit-reversing key, however, is attended with difficulty, and opposes an obstacle to the practical working of such a system.

25 One of the main objects of my invention is to obviate this difficulty, and I do this by using an ordinary make-and-break key in conjunction with an electrically-controlled reverser, by means of which the operation of reversing the current through the induction-coil is performed by a battery, and not directly by the hand of the operator. In applying this combination I use but one battery for operating the receiver, the reverser, and the induction-coil, dividing

30 the circuit from such battery into three branches, in the manner hereinafter set forth. I also use such switches and other instruments as are necessary for the successful operation of the system, the details of the construction and 35 mode of operation of which will be more fully understood by reference to the accompanying drawing.

The figure is a diagram showing my improved arrangement of circuits and the relations of the several instruments used in conjunction therewith.

55 A is the main or signaling line extending between two or more stations.

B is the primary of the induction-coil at one of the stations or terminals, and C the secondary of the same. The main circuit branches at the induction-coil, one branch including the secondary and going to ground at D, the other branch leading to a switch-key, E, the contact-plate of which is grounded at D'. In the main 60 line is a polarized relay, F.

The reverser which is used consists of an electro-magnet, G, in face of the pole of which is a spring-actuated vibrating armature, H. The free end of this armature is provided with 65 contact-points a a, situated between contacts b c, carried by two spring-actuated levers, K L. Between other contacts, d e, on these two levers K L is a pair of stationary contacts, f g, and these parts are so related that when the 70 armature H is moved slightly toward the magnet the contacts c a and d f are brought together and the others separated; or, when the movement is in the opposite direction the contacts b a and g e are brought together and the 75 others separated.

M is the battery. Its circuit is divided into three branches. One, formed by the wires m n o, includes the magnet G and an ordinary circuit-closing key, O. Another, formed by 80 wires m p n, includes the sounder or other form of receiver, and is partly through the frame and armature-lever of the polarized relay. The third branch is formed by wires m t to the armature H of the magnet G, from 85 whence it extends through the primary of the induction-coil by wire s and back to the battery by the wire w, the switch-key P, and wire n. At the other terminal or station are the 90 same devices arranged in the same manner as here shown.

The operation of the system is as follows: In order to transmit signals by means of the key O, the switch-key E is opened, so that the line or main circuit is grounded through the secondary of the induction-coil. The switch-key P, on the other hand, is closed, so as to bring the contacts f g into connection with the battery. The key O is then operated to make 95

and break the circuit through the magnet G. On closing the branch including this magnet the armature H is attracted toward the magnet and a current sent through the primary of the induction-coil. This induces a current on the line which operates the polarized relays at the sending as well as the receiving stations. On raising the key O the circuit through the magnet G is interrupted, a current-impulse of opposite direction to the first is sent through the primary of the induction-coil by the reaction of the armature H, and the relay-armatures shifted to their original position. When not sending by key O, the operator closes this key E, so as to short-circuit the primary of the induction-coil, and opens key P. Current impulses coming on the line operate the polarized relay and the receiving-instrument in the usual way.

20 The invention is obviously not limited to any specific form of the several instruments described, as any others that perform the same functions may be used.

What I claim is—

25 1. In a system for telegraphing by induction, the combination, with an induction-coil, of a circuit-closing key and an electro-magnetic reverser operated by the key for reversing the circuit through the primary of the induction-coil, as herein set forth.

2. In a system for telegraphing by induction, the combination, with an induction-coil, of an electro-magnetic reverser and a circuit-closing key arranged in branches of the same circuit, in the manner set forth.

35

3. In a system for telegraphing by induction, the combination, with an induction-coil, of an electro-magnetic circuit-reverser, a circuit-closing key, a polarized relay, and receiving-instrument, the primary of the induction-coil, 40 the circuit-reverser, key, and receiver being included in branches of one circuit, as and for the purpose set forth.

4. In a system for telegraphing by induction, the combination, with a main line including a polarized relay and branched, whereby it is adapted to be grounded either through or around the secondary of an induction-coil, of a local circuit divided into three branches, one branch including the electro-magnet of a 50 circuit-reverser and a circuit-closing key, another branch including the primary of the induction-coil and the circuit-reversing devices, and the third branch the receiving-instrument and the controlling or circuit-closing portions 55 of the relay, all as set forth.

MOSES G. FARMER.
